UNITED STATES PATENT OFFICE.

PATRIK ANDERSSON, OF NEW YORK, N. Y.

PHOTOGRAPH-PRINTING MACHINE.

Application filed October 12, 1921. Serial No. 507,244.

To all whom it may concern:

Be it known that I, PATRIK ANDERSSON, a citizen of Sweden, and a resident of the city of New York, borough of Manhattan, 5 in the county and State of New York, have invented a new and Improved Photograph-Printing Machine, of which the following as a full, clear, and exact description.

This invention relates to photograph 10 printing machines and has for an object to provide a machine in which the time of cycle of printing operation is decreased to a minimum.

Another object of the invention is to provide 15 a photographer's printing machine which is especially designed to decrease the time of cycle of printing operation without diminishing the various adjustments required by professional photographers.

20 A still further object of the invention is to provide a photograph printing machine wherein the print when complete is discharged substantially simultaneously with the application of a new sensitized sheet.

25 In the accompanying drawings—

Figure 1 is a side view of a machine disclosing one embodiment of the invention, the same being shown open and ready to receive the print paper.

30 Figure 2 is a front view of the structure shown in Figure 1.

Figure 3 is a sectional view through Figure 4 approximately on line 3—3.

35 Figure 4 is a sectional view through Figure 3 on line 4—4, the same illustrating substantially a front view of the frame and associated parts shown in Figure 2.

Referring to the accompanying drawings by numeral, 1 indicates a frame or support 40 which may be of any desired material and which acts to support a box 2 formed of any suitable material. This box is shown as a rectangular box positioned at an angle so that the operator may more readily place the

45 print paper in position. A foot pedal 3 is provided near the bottom of the frame 1 and connected to a rock shaft 4 which when rocked, will swing the arm 5 rigidly secured thereto, said arm in turn being pivotally

50 connected with a link 6 pivotally connected at 7 to a fitting 8 secured to the arm 9. The arm 9 is pivotally connected at 10 to the frame 1 and carries fittings 11 and 12 for pivotally connecting the links 13 and 14 to

55 arm 9. Link 13 is pivotally connected at 15 with the fitting 16 secured to the arm 17 car-

rying an extension 18 on which a lifter 19 is pivotally mounted and held in a given position by a suitable spring 20.

When the extension 18 is swung upwardly 60 as arm 17 is swung downwardly, lifter 19 strikes against the projection 21 so as to be swung slightly and thereby move out of the path of the lever 22. Before the lifter 19 has been moved out of engagement with the lever 22, said lever is swung on its pivotal supporting rod 23 and has rocked through the arm 24' the shaft 24 sufficiently to move the stop 25 out of the path of movement of the print 26 whereby said print may be slid 70 downwardly into the box or receptacle 27.

It will be noted that the shaft 24 carrying the stop or door 25 is pivotally mounted in suitable journals secured to the frame 28, which frame is slidable along the side angle 75 bars 29 and 30. These angle bars and associated parts are identical so that a description of one will apply to both. The frame 28 carries a lug 31 having an overhanging shoulder 32 as shown in Figure 4 which 80 partially encircles the angle bar 29 so as to hold the parts together. The angle bar 29 extends from the front of the machine to the rear and is journaled on the shaft 23 so that the frame 28 may be readily swung upwardly whenever desired. A short angle piece 33 is secured to the frame 28 above the lug 31 and carries a spring 34 acting against the end 35 of the pivotally mounted brake 36, which brake normally bears against one face 85 of the angle bar 29 and, consequently, frictionally locks the frame 28 in any adjusted position.

By this construction and arrangement, the angle bar 29 may be slid readily toward and 90 from the rear of the machine and may be swung upwardly at any time. The frame 28 is provided with a longitudinal slot 37 through which the clamping bolts 38 and 39 extend, said bolts acting to clamp the centering arms 40 and 41 in any desired adjusted position along the frame 28. These arms are provided with side covering plates 42 and 43 which cover that part of the glass 44 carried by the box 2 which is not exposed between the arms 40 and 41. Co-acting with the arms 40 and 41 is a negative holding plate 45 having a central notch 46 and a plurality of side notches 47 arranged in regular stepped order for receiving negatives of different 100 sizes. The construction is provided to receive glass negatives and after the negative

has been properly positioned in one of the notches of plate 45, members 40 and 41 are moved slightly over the edges of the negative and then the bolts 38 and 39 are tightened. The negative and the paper guiding members 40 and 41 are then in position for receiving print paper. A pressure pad 48 is provided which is formed with a suitable soft face for pressing against the paper and with a back of any kind, said back being provided with a strap or sleeve 49 adapted to slide over the arm 50 rigidly secured to shaft 51 by a set screw or other suitable means. A spring hook 52 is positioned as shown in Figure 1 to snap over the sleeve 49 and thereby lock the pad 48 in place. These pads are removable that one may be provided of proper size to fit between the arms 40 and 41 when pedal 3 has been depressed. A member 53 is rigidly secured to shaft 51 and is acted upon by a retractable spring 54 for normally holding the parts as shown in Figure 1. An arm 55 is also rigidly secured to shaft 51 and is pivotally mounted at 56 to the link 14 whereby whenever pedal 3 is depressed, these members will be moved for swinging the pad 48 downwardly and against the print paper placed on the negative supported on the glass plate 7 and by the plate 45. As soon as the pedal 3 is released, spring 54 will move the parts back again quickly to the position shown in Figure 4 and said movement will cause the lifter 19 to be raised and thereby swing the lever 22 upwardly a sufficient distance to move the stop 25 a sufficient distance to allow the printed paper to automatically slide down into the receptacle 27 or in case it should fail to move automatically, the operator may give the same a slight push as he places the next print paper in position. In this way there is no loss of time in applying and exposing the print paper and also by reason of the adjustment of the arms 40 and 41, the use of plate 45 and associated parts, there is a minimum loss of time in adjusting the parts to receive different sized negatives.

As shown in Figure 3, when the lever 22 is raised, the movement may be comparatively rapid but by reason of the dash pot structure 57, the return movement is comparatively slow whereby time is given for the printed paper to pass beneath the stop 25. The plate 45 is mounted as shown in Figures 2 and 4 so as to extend across the box 2 and be adjusted vertically toward and from the back or diagonally. Suitable clamping bolts 58 are used on each side, said bolts extending through suitable apertures 59 arranged in the angle bars 60. In the box 2 a lamp 61 and a suitable reflector 62 are provided, said lamp and reflector being of any desired or preferred kind and connected up in any desired manner to a source of current. Preferably, the source of current is connect-

ed with a timing switch 63 and wires are laid to the lamp 61 and to the contact posts 64 and 65 which are brought into engagement when the pad 48 is pressing the print paper firmly against the negative. By this construction, light is provided immediately upon the pressing of the print paper against the negative and the light is automatically turned off when the pad is elevated or the light may be turned off at a predetermined or set time by an automatic time switch before the pad is elevated.

During the printing operation, in case the stop 25 should not be opened properly or should close too soon, a manually actuated lever 66 may be used, said lever being pivotally mounted at 67 on the frame 28 and connected to a link 68 on the crank member 69 secured to the shaft or rod 24.

What I claim is:-

1. A photographic printing machine comprising a closed box having a glass top, a lamp for illuminating the box, means for supporting a negative on said glass top, means for supporting said negative in place, arms for guiding the print paper to said negative, said arms being formed with means for covering that part of the glass not covered by the negative, a pad for pressing a sheet of print paper against said negative, manually actuated means for moving the pad into an operative position for pressing the print paper against the negative, and means for causing said lamp to be lighted as the pad presses the paper, said means acting to turn out the lamp as the pad leaves the paper.

2. A photographic printing machine comprising a box having a glass top, a pair of angle bars hinged to said box so as to swing toward and from the plane of the glass top, a frame slidably longitudinally of the angle bars and over said glass top, said frame being connected with said angle bars, said frame being formed with a longitudinal slot therein, a pair of adjusting arms for centering the printing paper on said top, means extending through said slot for clamping the arms to said frame, a print receiving container arranged adjacent said glass top, a pad for pressing a piece of print paper on the negative on said top, and means for illuminating the interior of the box and the negative when the pad is pressing against said print paper.

3. A photographic printing machine of the character described comprising a glass support for supporting a negative, a pair of guiding bars arranged at each end of the glass support, a frame slidably mounted on said bars and adapted to slide transversely of said support, a pair of clamping and centering arms slidably carried by said frame for centering the negative on said support, a pad for pressing a piece of print paper

against said negative, and means for illuminating the negative while the pad is pressing the print paper against the same.

4. A photographic printing machine comprising a supporting transparent plate arranged at an angle to the horizontal whereby paper positioned thereon will slide off under the action of gravity, means for supporting a negative on said supporting plate, 10 a stop for supporting a piece of print paper on said negative, a pad for pressing said print paper against the negative, means for illuminating the negative when the pad is pressing the print paper against the negative, automatically actuated means for moving said stop out of the way of said print paper when the pad is removed from in contact with the print paper, and manually actuated means for moving said stop to a 20 position out of the way of said print paper.

5. A photographic printing machine comprising a closed box or container having a glass top, a notched plate for receiving a negative plate while the same rests on the 25 glass top, a movable plate adjacent said notched plate for supporting on said negative plate a sheet of printing paper, a pad for pressing the paper against the negative, and means for associating the pad with the movable plate so that the plate and the pad move away from the printing paper coordinately.

6. A photographic machine of the character described, comprising a box having a

glass top, a pair of pivotally mounted angle 35 bars carried by said box at the sides, a frame slidably mounted on said angle bars between the two and slidable over the glass top of the box, said frame being formed with a pair of slots, a centering arm slidably held in each slot, said arms being adapted to be brought against the side edges of the negative plate on said glass top to clamp said plate in place, pivoted means for pressing a piece of print paper placed on said negative plate, manually-actuated means for moving said pivoted means on said print paper and spring means for automatically moving away from the print paper said pivoted means when said manually-actuated means are released.

7. A photographic printing machine comprising a box having an inclined glass top, a movable stop arranged adjacent the lower end of said glass top for preventing a piece of print paper laid on said top from sliding off, a swinging pad movable on said print paper to press the same on said top, means for illuminating said box as said pad moves toward the top, means connecting the stop of the pad so as to slidably raise said stop as the pad moves away from the top to permit said print to slide off the top, and a container in the front of said printing machine for receiving the print slid from the top.

PATRIK ANDERSSON.
